F. M. STEINER

TOWEL CABINET

Filed March 20, 1922

INVENTOR
FRANK M. STEINER

By *Paul H. Paul*
ATTORNEYS

UNITED STATES PATENT OFFICE.

FRANK M. STEINER, OF MINNEAPOLIS, MINNESOTA, ASSIGNOR TO STEINER SALES COMPANY, OF SALT LAKE CITY, UTAH, A CORPORATION OF UTAH.

TOWEL CABINET.

Application filed March 20, 1922. Serial No. 545,174.

To all whom it may concern:

Be it known that I, FRANK M. STEINER, a citizen of the United States, resident of Minneapolis, county of Hennepin, State of Minnesota, have invented certain new and useful Improvements in Towel Cabinets, of which the following is a specification.

My invention relates to that type of cabinet adapted to receive a plurality of rolls of towel, with provision for using one roll at a time, the cabinet being so constructed that the janitor or person in charge of the toilet room can, at any time when either roll is exhausted, place the clean roll in reserve position in the cabinet ready to be made use of when the towel in use has been exhausted. It is therefore unnecessary for either the laundryman or the janitor to remove a partially used roll and return it to the laundry, which is often done, resulting in waste of the towel, the attendant fearing that the partially used towel will not last until the laundryman makes another trip.

My invention also eliminates the necessity of examining the cabinet as frequently as the janitor would do if provision was made for only one roll in the cabinet.

A further object is to keep the reserve towel roll in a position where it cannot be used until the towel in use is exhausted.

A further and particular object is to provide improved means whereby the second towel web can be easily and quickly placed in position for use when the web of the first towel is exhausted.

Other objects of the invention will appear from the following detailed description.

The invention consists generally in various constructions and combinations, all as hereinafter described and particularly pointed out in the claims.

In the accompanying drawings forming part of this specification,

Figure 1 is a vertical sectional view through a towel cabinet embodying my invention,

Figure 2 is a front view of the same,

Figure 3 is a detail sectional view through the towel grippers, one gripper plate being shown partially removed from its sockets,

Figure 4 is a front view of a gripper showing the support for the towel and the hinged gripper,

Figure 5 is a detail sectional view of the measuring rod.

In the drawing, 2 represents the cabinet having chambers 3 and 4 in the lower portion for the clean towel rolls 5 and 6, the chambers being preferably separated by a rigid shelf 7 on which the roll 6 is supported. A curved wall 8 extends from the rear wall 9 forwardly and downwardly to the base of the cabinet and forms a chamber 10 in the lower front of the cabinet into which the soiled towel is delivered, access thereto and to the chambers 3 and 4 being had through a suitable door 11. The upper portion of the cabinet has an opening 12 therein and beneath this opening is an inclined shelf 13 which serves to direct the loose end of the towel toward the chamber 10 and also limits the downward movement of the hands of the user as he pulls on the clean depending portion of the towel.

A wall 14 is provided at the rear of the chambers 3 and 4 and at the top of this wall is an opening 15 through which the webs of clean toweling are carried to the grippers above. The wall 9 is preferably inwardly inclined toward the top and allows the towel web to slide easily thereon toward the forward gripper. These grippers are of corresponding construction and comprise sockets 16 and 16^a mounted on the side walls of the cabinet and adapted to receive loose bars 17 and 17^a having their ends fitting into the sockets and freely slidable vertically therein.

I have shown flat removable bars but it will be understood that rolls may be substituted therefor, if preferred, the towel web sliding over the peripheries of the rolls and clamped thereon by the action of the grippers in substantially the same way as the towel web is clamped on the bars.

Brackets 18 are secured to the side walls of the cabinet and have bearings for shafts 19 of the gripper plates 20 arranged in position to clamp the towel webs against the upper surfaces of the bars 17 and 17^a, said gripper plates having flanged lower edges 21 which are engaged by the towel webs when they are pulled forwardly for tilting the gripper plates and clamping the webs against the bars 17 and 17^a.

As shown in Figure 1, the web from the roll 6 is carried up to the forward gripper, the loose end being passed over the bar 17 and downwardly between this bar and the gripper 20, while the web from the roll 5 is 110

carried up in a similar manner to the rear gripper and suspended thereon. A person standing in front of the cabinet will pull downwardly on the web of the roll 6 until his hands are checked by the shelf 13, then he can pull the towel forwardly through the opening 12 to a position for convenient use and then forward pull on the towel will tilt the plate 20 and cause its upper edge to grip the web and clamp it against the bar 17, thereby preventing further feed or pull of the towel until the loose portion is dropped and assumes a substantially vertical position. When the towel 6 has been exhausted, the person in charge of the cabinet may remove the forward bar 17 and substitute therefor the rear bar 17^a with the towel hanging thereon and the operation described may be repeated.

In other words, the rear bar with the towel web hanging thereon is substituted for the forward bar when the towel on the forward plate is exhausted.

If the forward towel, or the one that is used first becomes exhausted, the person next desiring to use the cabinet can reach through the opening in the front and grasp the loose end of the reserve towel and drawing down thereon obtain a sufficient length for wiping purposes. This use may continue until the janitor or other person in charge of the cabinet has opportunity to transpose the bars, and move the towel roll 5 from the chamber 3 to the chamber 4. Then when the laundry man calls, he can remove the soiled towel from the compartment 10 and either he or the janitor will place a fresh reserve roll in the chamber 3 and carry the loose web thereof up over the rear bar or support where it can be seen and be readily accessible to the towel users when the forward roll is again exhausted. In this way, I provide a continuous unbroken supply of clean toweling to the users of the cabinet. There is no period when the cabinet is not adapted to deliver a clean section of towel.

I prefer also to provide a rod 22 loosely fitting the holes 23 in the side walls of the cabinet. This rod can be placed in any of the opposite holes shown and becomes an adjustable measuring device that will measure or determine a wiping surface of the towel of eight, ten or twelve inches, as desired. The towel web is passed under the rod, which operates to limit the upward movement of the hands with the towel, as indicated in Figure 1, and this movement can be increased or decreased by the vertical adjustment of the rod.

The particular advantage of this cabinet lies in the fact that the towel supporting bars forming the normally stationary portions of the grippers may be easily and quickly removed or reversed in position to allow one towel to be substituted for another

and a supply of clean toweling always maintained without any interruption at a point where it can be conveniently reached by the users of the cabinet.

I claim as my invention:

1. A towel cabinet comprising a support, a plurality of rolls of clean towel therein having their webs one in advance of the other, a plurality of feed regulating devices for said rolls, said devices comprising removable supports one in advance of the other over which the webs of towel pass, and gripper plates actuated by outward pull on the towel webs for clamping said webs against said supports. 70

2. A towel cabinet comprising a support, a plurality of rolls of clean towel therein, feed regulating devices arranged one in front of the other, for the webs of clean towel, said devices comprising bars removable from their supports for transposition therein, and over which bars the towel webs pass, and means for clamping the towel webs against said bars. 80

3. A towel cabinet comprising a casing, a plurality of towel webs therein, grippers arranged to receive the webs of clean towel, said grippers comprising forward and rear bars removable from their supports for transposition therein, and over which bars the webs pass and depend one in front of the other, and said grippers including means for clamping the towel webs against said bars when forward and outward pull is applied to the webs. 90

4. A towel cabinet comprising a casing, plurality of towels therein, towel grippers mounted in the upper portion thereof and comprising plates and sockets therefor in which said plates are removably mounted, the webs of clean towel depending from said plates and angles plates pivotally supported and engaged by the web of towel for clamping it against said removable plates. 100

5. A towel cabinet comprising a support for the rolls of clean towel, feed regulating devices over which the towel webs pass, one feed device being utilized for the towel in use and the other for the reserve web, and including loose bars and fixed supports, said bars being removable from their supports for transposition therein, to allow the web of the reserve towel to be substituted for the other when it has been used, the loose end of the reserve towel web being visible and accessible to the user when the first web of toweling is exhausted. 115

6. A towel cabinet comprising a support for the rolls of clean toweling, feed regulating devices over which the towel webs pass, one device being utilized for the towel in use and the other for the reserve web, the supports for the webs in said feed regulating devices being mounted for transposition to allow the web of the reserve towel to 120

130

- be substituted for the other when it has been used and means for increasing or decreasing the delivery of the towel and the length of wiping surface delivered to the user. 35
- 5 7. A towel cabinet comprising a support for the rolls of clean toweling, feed regulating devices over which the towel webs pass, one device being utilized for the towel in use and the other for the reserve web, the
- 10 supports for the webs in said feed regulating devices being mounted for transposition to allow the web of the reserve towel to be substituted for the other when it has been used and means for increasing or decreasing 15 the length of wiping surface delivered to the user, said means comprising a rod adjustable vertically in said support.
8. A towel cabinet comprising a support, main and reserve webs of clean towel, feed 20 regulating devices including bars loosely mounted in fixed supports said bars being removable from their supports for transposition one for the other, and adapted to support respectively the towel webs of the one 25 in use and the one in reserve, the reserve towel web being substituted for the one in use when it is exhausted, and means for limiting the length of wiping surface delivered to the user.
- 30 9. A towel cabinet comprising a support for rolls of clean towel, feed regulating devices adapted to support the towel webs of the one in use and the one in reserve, the reserve towel web being substituted for the
- one in use when it is exhausted, and means 35 for limiting the length of wiping surface delivered to the user, said means comprising a rod vertically adjustable with which the towel web in use engages.
10. A towel cabinet comprising a casing 40 having a towel delivery opening, a plurality of towel rolls arranged in said casing, bars loosely mounted one in advance of the other on fixed supports in said casing adjacent said opening, said bars being removable from their supports for transportation therein, said bars supporting the loose ends of the towel webs one in front of the other, and having means for gripping said webs and regulating the feed thereof, the 45 rear bar being substituted for the forward bar when the forward towel roll is exhausted.
11. A towel holder and a plurality of towel rolls arranged therein, fixed bearings 50 having removable bars arranged one in advance of the other, over which the loose ends of the towel webs are supported, the forward web being accessible to users of the holder and covering and concealing the rear web, the rear web being accessible to users 55 when the forward web is exhausted, and said bars being removable from said holder for transposition therein to allow the rear towel web to be substituted for the forward one.
- In witness whereof I have hereunto set 60 my hand this 16" day of March, 1922.

FRANK M. STEINER.
